(57) **CLAIM**

The ornamental design for a display panel, as shown and described.

DESCRIPTION

FIG. 1 is a front elevational view of a first embodiment of a display panel showing our new design, with a middle portion between two dot-dash broken lines omitted; FIG. 2 is a rear elevational view, with a middle portion between two dot-dash broken lines omitted thereof; FIG. 3 is a left-side elevational view thereof; FIG. 4 is a right-side elevational view thereof; FIG. 5 is a top plan view, with a middle portion between two dot-dash broken lines omitted thereof; FIG. 6 is a bottom plan view, with a middle portion between two dot-dash broken lines omitted thereof; FIG. 7 is an enlarged view of portion 7-7 in FIG. 1; FIG. 8 is an enlarged view of portion 8-8 in FIG. 1; FIG. 9 is an enlarged view of portion 9-9 in FIG. 1; FIG. 10 is an enlarged view of portion 10-10 in FIG. 1; FIG. 11 is a front, left-side and bottom perspective view thereof; FIG. 12 is an enlarged view of portion 12-12 in FIG. 11 thereof; FIG. 13 is an enlarged view of portion 13-13 in FIG. 11 thereof; FIG. 14 is a front elevational view of a second embodiment of a display panel showing our new design, with a middle portion between two dot-dash broken lines omitted; FIG. 15 is a rear elevational view, with a middle portion between two dot-dash broken lines omitted thereof; FIG. 16 is a left-side elevational view thereof; FIG. 17 is a right-side elevational view thereof; FIG. 18 is top plan view, with a middle portion between two dot-dash broken lines omitted thereof; FIG. 19 is bottom plan view, with a middle portion between two dot-dash broken lines omitted thereof; FIG. 20 is an enlarged view of portion 20-20 in FIG. 14 thereof;

(Continued)

FIG. 21 is an enlarged view of portion 21-21 in FIG. 14 (56) thereof;

FIG. 22 is an enlarged view of portion 22-22 in FIG. 14 thereof;

FIG. 23 is an enlarged view of portion 23-23 in FIG. 14 thereof;

FIG. 24 is a front, left-side and bottom perspective view thereof;

FIG. 25 is an enlarged view of portion 25-25 in FIG. 24; and, FIG. 26 is an enlarged view of portion 26-26 in FIG. 24.

The evenly spaced dashed lines depict portions of the display panel and form no part of the claimed design. The dot-dash broken lines in FIG. 1, FIG. 7, FIG. 9, FIG. 11, FIG. 13, FIG. 14, FIG. 20, FIG. 22, FIG. 24 and FIG. 26 define the boundary of the claimed design and form no part of the claimed design. The two dot-dash broken lines in FIG. 1, FIG. 2, FIG. 5, FIG. 6, FIG. 11, FIG. 14, FIG. 15, FIG. 18, FIG. 19 and FIG. 24 show a symbolic break in the length of the display panel. The two dot-dash broken lines, as well as any portion of the article between the two dot-dash broken lines, form no part of the claimed design. Areas of the display panel that appear in different shades of gray show a contrast in appearance. The oblique shade lines in FIG. 1, FIG. 7, FIG. 8, FIG. 9, FIG. 10, FIG. 11, FIG. 12, FIG. 13, FIG. 14, FIG. 20, FIG. 21, FIG. 22, FIG. 23, FIG. 24, FIG. 25 and FIG. 26 show translucency. The three dot-dash broken lines in FIGS. 7, 8, 9, 10, 12, 13, 20, 21, 22, 23, 25 and 26 indicate the outer limits of the enlarged views and form no part of the claimed design.
